CLAIM

The ornamental design for an internal combustion engine cylinder head, as shown and described.

DESCRIPTION

FIG. 1 is a left front perspective view of an internal combustion engine cylinder head according to the present invention.

FIG. 2 is a top plan view of the internal combustion engine cylinder head of FIG. 1.

FIG. 3 is a left side view of the internal combustion engine cylinder head of FIG. 1.

FIG. 4 is a front view of the internal combustion engine cylinder head of FIG. 1.

FIG. 5 is a rear view of the internal combustion engine cylinder head of FIG. 1.

FIG. 6 is a right side view of the internal combustion engine cylinder head of FIG. 1; and,

FIG. 7 is a bottom view of the internal combustion engine cylinder head of FIG. 1.

The broken lines in the drawing views are included for the purpose of illustrating portions of the internal combustion engine cylinder head that form no part of the claimed design.
